CLAIM

The ornamental design for a dental appliance sanitizing device, as shown and described.

DESCRIPTION

FIG. 1 is a perspective view of a first embodiment of a dental appliance sanitizing device showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof;

FIG. 7 is a front elevational view thereof;

FIG. 8 is a perspective view of a second embodiment of a dental appliance sanitizing device showing my new design;

FIG. 9 is a top plan view thereof;

FIG. 10 is a bottom plan view thereof;

FIG. 11 is a right side elevational view thereof;

FIG. 12 is a left side elevational view thereof;

FIG. 13 is a rear elevational view thereof; and,

FIG. 14 is a front elevational view thereof.

The broken lines in the drawing views are included for the purpose of illustrating portions of the dental appliance sanitizing device that form no part of the claimed design.
